The ornamental design for a long arm sewing machine for quilts, as shown and described.

DESCRIPTION

FIG. 1 is a top, front, left perspective view of a long arm sewing machine for quilts, showing our new design;
 FIG. 2 is a top, back, right perspective view thereof;
 FIG. 3 is a top plan view thereof;
 FIG. 4 is a bottom plan view thereof;
 FIG. 5 is a front elevational view thereof;
 FIG. 6 is a rear elevational view thereof;
 FIG. 7 is a right side elevational view thereof; and,
 FIG. 8 is a left side elevational view thereof.
 The broken lines in the figure drawings represent unclaimed environment and form no part of the claimed design.
